UNITED STATES PATENT OFFICE

2,604,675

DEVICE FOR HOLDING SCREEN AND STORM
WINDOWS

Delbert O. Seaman, Des Moines, Iowa

Application September 7, 1948, Serial No. 48,041

1 Claim. (Cl. 20—55)

1

The principal object of my invention is to provide a means for successfully holding either a screen window or storm window to a window frame.

A further object of this invention is to provide a screen and storm window holding means that permits the easy and quick removal or replacement of the screen or storm window without the use of tools.

A still further object of my invention is to provide a screen, storm window, or like holding means that may be installed on window frames already in use.

A still further object of this invention is to provide a screen and storm window holding means that permits the placement or removal of the screen or storm window by the user from a point inside the building, thereby eliminating the dangerous use of outside ladders and like.

A still further object of my invention is to provide a storm window construction that permits the limited opening of the storm window when desired.

A still further object of my invention is to provide a screen and storm window holding means that holds the screen or storm window securely and without objectionable rattling.

Still further objects of my invention are to provide screen and storm window holding means that is durable in use, economical in manufacture, and refined in appearance.

These and other objects will be apparent to those skilled in the art.

My invention consists in the construction, arrangement, and combination of the various parts of the device, whereby the objects contemplated are attained as hereinafter more fully set forth, pointed out in my claim, and illustrated in the accompanying drawings, in which:

Fig. 1 is an outside perspective view of a storm window being held by my means.

Fig. 2 is a longitudinal vertical sectional view of my construction taken on line 2—2 of Fig. 1 and more fully illustrates its construction.

Fig. 3 is an enlarged cross-sectional view of a portion of my construction taken on line 3—3 of Fig. 1.

Fig. 4 is an inside view of my device taken on line 4—4 of Fig. 2.

Fig. 5 is a longitudinal vertical sectional view of my construction, similar to Fig. 2, but with the frame holding a screen instead of a storm window.

One of the most objectionable tasks is the periodical changing of storm windows to screens

2

in the spring and the changing of the screens to storm windows in the fall. The work has to be done outside the building and usually on a ladder. In this connection many accidents do occur, as tools are usually necessary to complete the installation. Many people hire some one skilled in the art to do the work. Furthermore, after the storm windows are installed the user can not open them if the occasion makes such opening desirable. I have overcome such objections as will hereinafter be appreciated.

Referring to the drawings I have used the numeral 10 to generally designate an ordinary window opening frame. Such frames hold a glass window, not shown in the drawings. Obviously, such window frames are common in most all buildings, and it is to such a window frame that I attach my screen and storm window holding means. Storm windows and screens are interchangeable and have the usual rectangular frame 11. If the item be a storm window, the frame 11 will have a glass 12, as shown in Fig. 1. On the other hand, if the item is a screen, the frame 11 will be enclosed with a screen wire mesh 13.

20 In either event, the frame 11 will be common and has its marginal edges capable of fitting into the usually prepared opening of the window frame 10, and to the outer side of the glass window the frame 11 usually supports. On the outside of the window frame and overlapping its two opening corners, respectively, I install two bracket housing members 14 and 15, as shown in Fig. 1. While these two brackets are pairs, they are not duplicates, as one must be to the left side, and the other must be to the right side. They are secured by any suitable means such as by screws, nails, bolts or like 16. The front side of each of these brackets extends downwardly and outwardly, as shown in Fig. 3. Also each bracket member has

35 its outer side 17 closed and its inner side 18 only partially closed, inasmuch as its lower marginal edge extends downwardly and forwardly, as shown in Fig. 2. This construction permits the upper end of the frame 11 to be inserted into the window frame and under the overlapping bracket members, with the lower end of the frame extending outwardly from the main window, as shown by dotted lines in Fig. 2. Inside each bracket I mount a curved vertical leaf spring 19 fastened at one end to the underside of its bracket member, as shown in Fig. 3. By this arrangement when a frame 11 is placed into the window frame a spring 19 will be yieldingly bearing on each outer upper corner of the screen or storm window frame 11. This yielding contact

will permit the ready removal or replacement of a frame 11, but will prevent any accidental movement of the upper end of the frame outwardly from the main window frame 10. By the outer side of the brackets being closed and positioned just outside the side planes of the frame 11, the frame 11 will be properly positioned, for its upper end portion to be guided into the window frame opening. If the frame 11 carries a screen, as shown in Fig. 5, the lower end portion is pulled or forced into the window opening, and hooks 20 fastened to the main window frame are detachably hooked into screw eyes 21 on the frame 11. By this means the top of the frame 11 will be held in place by the spring bracket elements and the lower end of the frame will be held by the hooks 20 and eyes 21. To remove the frame 11 it is merely necessary to unhook the hooks 20, push the lower portion of the frame 11 outwardly, and then lower the frame from the bracket members. The frame 11 is just as easily replaced. No tools or special skill are required. The removal or replacement of the frame takes but a moment's time. In the case of a screen, no further mechanism is required or desired. In the case of storm windows, however, there are times when the user wishes to open the storm window a limited amount. Therefore, at each side of the main window frame I secure at its upper end a coil spring 22, as shown in Fig. 4. Secured to the lower end of each spring is a chain, cable or like flexible element 23. Imposed in the chain or like and near its lower end is a holed tab 24, capable of being placed around a downwardly extending hook 25 on the inner side of the frame 11, as shown in Fig. 4. These tabs 24 and hooks 25 are so positioned that the springs will be under tension when they are fastened together. By this construction the frame 11 will be yieldingly held upwardly, even though the lower end of the frame is pushed outwardly from the window frame 10, as shown by dotted lines in Fig. 2. If it is desired to maintain this position of the window frame 11, I have provided elongated hooks 26 secured to the main window frame and capable of entering screw eyes 27 on the frame 11, as shown by dotted lines in Fig. 2. Obviously, the springs 22 and chains 23 will hold the frame 11 upwardly within the bracket members and these hooks and eyes 26 and 27 will hold the lower portion of the frame outwardly a limited distance, thereby permitting air to pass into the window. When it is desired to close the storm window it is merely necessary to unhook the hooks 26 and the springs will return the frame 11 to a closed position. When the tabs are engaging the hooks 25, the springs 22 will also yieldingly hold the frame 11 from rattling and this is true whether the storm window is open or closed. A guard shield 28 may be placed above each of the screw eyes to insure against the accidental detachment of the hooks 26. When the frame 11 is in closed position the hooks 20 should be inserted in the screw eyes 21. In the case of screens and at other times, it will not be necessary to employ the springs 22 and chains 23. When this is the case the tabs 24 are detached from the hooks 25 and then attached to neutral hooks 29 on the main window frame, as shown in Fig. 5. A handle 30

may be placed on the lower portion of frame 11 to facilitate its handling. A chain 31 may also be installed on the main frame 10 below each of the springs 22. In case of double sash windows the fastening of the upper ends of the springs 22 should be at a point below the upper frame of the lower window when the lower window is in closed position, and the hooks 25 and 29 should be relocated accordingly. The stop guides 31 also limit the downward movement of the coil springs 22 so that after the coil springs have been completely extended to this limit the weight of the frame 11 when open at the bottom will be supported substantially by the members 31. Some changes may be made in the construction and arrangement of my device for holding screen and storm windows without departing from the real spirit and purpose of my invention, and it is my intention to cover by my claim, any modified forms of structure or use of mechanical equivalents which may be reasonably included in its scope.

I claim:

In combination, a detachable frame, a window frame having an opening for receiving the detachable frame, two spaced apart rigid brackets secured to the window frame; said rigid brackets each having a portion that extends below the top plane of the detachable frame receiving opening of the window frame, a resilient means in each of said brackets exerting solely an inward force against the top portion of said detachable frame, an elongated resilient means secured at its ends to the window frame and detachably secured to the detachable frame respectively; said elongated resilient means being secured to the window frame at a point substantially above its point of attachment to the detachable frame; and the points of attachment of said elongated resilient means being spaced farther apart than the constricted length of said elongated resilient means; said elongated resilient means being secured to the window frame at a point spaced inwardly from the innermost portion of the opening in the window frame for receiving the detachable frame; whereby said bracket members positively limit the outward movement of the upper end of said detachable frame with respect to said window frame, and whereby said elongated resilient means yieldingly holds one side of the detachable frame upwardly and one side of the lower end of the detachable frame inwardly.

DELBERT O. SEAMAN.
